George Arnold Inventor
Franklin St. Young Attorney

UNITED STATES PATENT OFFICE.

GEORGE ARNOLD, OF ROSEMONT, QUEBEC, CANADA.

BLANK FOR ENVELOPS OF TWO SIZES.

1,315,070.

Specification of Letters Patent. Patented Sept. 2, 1919.

Application filed May 17, 1919. Serial No. 297,817.

To all whom it may concern:

Be it known that I, GEORGE ARNOLD, a subject of the King of England, residing at Rosemont, in the city of Montreal, Province 5 of Quebec, Canada, have invented certain new and useful Improvements in Blank for Envelops of Two Sizes; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in envelops and consists essentially in the provision of a blank so cut that the same may be folded and formed into 20 envelops of two distinct sizes.

The invention comprises a simple and efficient device of this character having various details of construction, combination and arrangement of parts which will be herein- 25 after fully described, shown in the accompanying drawings and then specifically described in the appended claim.

My invention is illustrated in the accompanying drawings which, with the letters of 30 reference marked thereon, form a part of this application, and in which:

Figure 1 is a plan view of the blank before being folded.

Fig. 2 is a view showing the top and bottom flaps folded.

Fig. 3 is a plan view showing three of the flaps folded.

Fig. 4 is a view of the blank before being folded.

Fig. 5 is a view showing the end flap folded.

Fig. 6 is a view showing the blank folded along the central transverse scored line.

Fig. 7 is a view showing the next step in 45 the folding of the parts.

Fig. 8 is a perspective view showing a portion of the folded envelop, illustrating the manner of interlocking of the flaps.

Fig. 9 is a detail view of the reverse and 50 front faces of the blank when folded to form the small envelop, and

Fig. 10 is a detail view of the rear of the large size envelop folded, as illustrated in Fig. 1 of the drawings.

Reference now being had to the details of 55 the drawings by numerals:

1 designates a blank having four flaps, designated respectively by numerals 2, 3, 4 and 5, the said flap 2 being the top flap and which is provided with elongated slits 6 disposed at an inclination to the length of the envelop. The top and end flaps are provided with a gummed surface 7 of adhesive material. The flap 4 is also provided with a gummed surface 8 and is slit as at 9 for the 60 purpose of forming a small sized envelop, as illustrated in Fig. 8 of the drawings, but has no function when the blank is folded to 65 form the envelop shown in Fig. 10.

In folding the flaps of the blank, shown 70 in Figs. 1 to 3 inclusive of the drawings, the top and bottom flaps are first folded, as shown in Fig. 2, after which the end flaps are folded with their tapering ends inserted in the slots 6, and by moistening the adhesive 75 surfaces the flaps may be sealed as will be readily understood.

When it is desired to fold the flap to form a small envelop shown in Fig. 9 of the drawings, the end flap 5 is folded over the face 80 of the blank in the manner shown in Fig. 5, after which the blank is folded along the transverse line 11 and the next step in the formation of the envelop consists of folding the doubled flap 4, which has two winged 85 portions 12 and 13, up against the double folded portion of the blank into the position shown in Figs. 7 and 8 of the drawings, after which the top double folded portion 2 is 90 bent down in the manner shown in Fig. 8, with one wing 12 underneath the double folded flap 2, while the flap 13 passes between the double folds of the flap 2. The last flap 3 to be folded is then inserted through the slot 6 in the manner shown in 95 Figs. 8 and 9 of the drawings, and the adhesive coating upon the flaps moistened, as well as the adhesive surface 8 adjacent to the slit 9, thus securely sealing the small size envelop, it being understood that the letter 100 is inserted in the envelop before the flap 3 is folded and sealed.

By the provision of an envelop embodying the features of my invention, it will be noted that a simple and efficient means is afforded 105 whereby the blank may be folded to form either a large or a small size envelop, as may be desired for various purposes.

What I claim to be new is:

A blank of paper adapted to be folded to form two sizes of envelopes, consisting of a sheet of paper, having an angled outlined top and end flaps, said top flap having slots parallel with the inclined edges, and the bottom flap having a central slitted portion, one end flap adapted to be folded against the face of the blank, and the latter thence 10 folded centrally along the slitted line forming double folds to the top, and bottom flaps

which are folded over each other, one of the wings formed by slitting the bottom flap adapted to be inserted between the double folds of the top flap and the other underneath the two folds of the top flap, and the remaining end flap inserted in one of the slots in the top flap, flaps having adhesive material to seal the parts folded together. 15

In testimony whereof I hereunto affix my 20
signature.

GEORGE ARNOLD.

Copies of this patent may be obtained for five cents each, by addressing the "Commissioner of Patents Washington, D. C."
